UNITED STATES PATENT OFFICE.

CHARLES S. CHURCHILL AND CHARLES C. WENTWORTH, OF ROANOKE,
VIRGINIA.

MEANS FOR VENTILATING TUNNELS.

SPECIFICATION forming part of Letters Patent No. 689,089, dated December 17, 1901.

Application filed July 15, 1901. Serial No. 68,375. (No model.)

To all whom it may concern:

Be it known that we, CHARLES S. CHURCHILL and CHARLES C. WENTWORTH, citizens of the United States, residing at Roanoke, county 5 of Roanoke, State of Virginia, have invented certain new and useful Improvements in Means for Ventilating Tunnels, of which the following is a specification.

Our invention relates to means for ventilating tunnels, and more particularly to an improvement upon the construction disclosed and claimed in our Patent No. 671,264, granted April 2, 1901.

The object of our invention is to provide 15 a construction of discharge-nozzle through which the air-blast is blown into the tunnel in the manner described in our prior patent, above mentioned, which will prevent the possibility of formation of eddies in the current 20 at certain points adjacent to said discharge-nozzle, such eddies tending to some extent to create a slight counter-current, and thus vary the velocity or flow of the current of air at the point where the eddies are formed:

25 In the operation of our improved ventilating means as disclosed in the patent hereinbefore mentioned we find that such eddies tend to form at or near the bottom of the tunnel, and they are due to the eccentricity of 30 the center of gravity of the air-blast with respect to that of the tunnel-section when the air-blast is discharged through a nozzle that is not symmetrical on all sides with respect to the central axis of the tunnel. Therefore 35 where the blast is discharged into the tunnel through an opening which extends around the arch and down the sides while there is a current on either side to balance the current on the other side of the tunnel there is no current at the bottom to balance that which is delivered at the top or apex of the air-blast opening. While these eddies do not materially affect the efficiency of our prior patented construction so far as the function of ventilation 45 of the tunnel is concerned, they are yet objectionable under some conditions in so far as they tend to create a counter-current, though to a slight extent, at points near the bottom of the tunnel, and therefore we regard means for avoiding or preventing them 50 to be in the direction of greater perfection,

and for this reason our present invention is an improvement upon our prior construction.

With the above object in view our invention consists in the novel construction herein- 55 after described and claimed with reference to the accompanying drawings, in which—

Figure 1 is a central longitudinal section of a portion of the tunnel, showing our invention applied to one end. Fig. 2 is a vertical 60 section on the line 2 2, Fig. 1. Fig. 3 is a longitudinal section of a modified form.

Referring to the drawings, in which the same reference characters refer to the same or corresponding parts in all the views, and in 65 which a ventilating plant operating upon the same principle as that disclosed in our prior patent is shown, the numeral 1 indicates a section of a tunnel, while the numeral 2 indicates the inner wall thereof, which tunnel 70 is of the usual cross-section. Within the walls of the tunnel is formed an air-chamber 3, extending around the sides and top of the tunnel, the outer wall 4 of said chamber being preferably inclined, while the inner wall 75 5 is parallel to the axis of the tunnel and is a prolongation of the inner wall 2 of the tunnel, thus forming a tapered chamber. The discharge-opening 7 for the air terminates the chamber 3 and is formed as in the prior patent. This discharge-opening, it will be observed, is formed by the inner wall of the tunnel and the extremity 6 of the inner wall of the chamber 3, said extremity being preferably tapered to reduce to a minimum the tendency 80 to the formation of eddies in the current of air discharged through the nozzle thus formed.

The outer end of the air-chamber is closed by an end wall 8 of the tunnel, through which 90 end wall is an opening to which is attached a discharge-pipe 9, extending from a blower 10 and driven by any suitable motor, such as an engine 11.

In our prior patent the tapered edge 6, 95 forming the inner wall of the contracted air-outlet, extends vertically, as indicated by dotted lines 3^a 3^a, Fig. 1, so that the air-blast is discharged simultaneously at all points around the top and sides of the tunnel at the 100 same velocity and in the same volume, and as a consequence there is a tendency for the

blast to form an eddy, as indicated by arrow A in Fig. 1, because of the fact that there is no current discharged at the bottom to counterbalance the current discharged at the top. 5 In order to overcome this objection, we have found that by forming the end of the wall 6^a on an incline downwardly in a direction contrary to the direction of air-blast as it leaves the nozzle, as shown in Fig. 1, the desired result is attained. This construction permits the air to leave the nozzle at points gradually approaching nearer the closed end of the chamber as the nozzle approaches the bottom or that side of the tunnel where there is no 15 discharge. The effect of this construction is to bring the center of gravity of the air-blast more nearly coincident with the center of gravity of the tunnel-section, so that there is no overbalancing of one portion of the blast 20 with respect to the other, and thus the eddies hereinbefore mentioned are avoided.

It should be noted that the relation between the inner wall of the tunnel and the inner wall of the chamber 3 is the same as in 25 our prior construction; but the area of the nozzle-opening gradually increases toward the bottom, as shown in Fig. 2.

Instead of inclining the entire edge of the discharge end of the chamber 3 from top to 30 bottom we may in many instances form this edge as shown in Fig. 3, where the inclined edge of the discharge end of the chamber is indicated by 6^b, which lies in an inclined plane beginning at a point slightly below the 35 crown of the tunnel on each side, such discharge end being then composed of a portion 18, lying in a vertical plane or in a plane at right angles to the axis of the tunnel, and an inclined portion 6^b, which lies in a plane in- 40 clined with respect to the other portion.

Other modified forms of the tapered discharge-opening may be used without departing from the spirit of our invention as hereinafter claimed, such forms being dependent 45 upon the cross-section of the tunnel, the linear extent of the nozzle with respect to the said cross-section, and the consequent relation between the centers of gravity of the tunnel-section and the air-blast, the essential 50 requisite being that the centers of gravity of the tunnel-section and the air-blast shall be made to approach as nearly to coincidence as it is possible to attain. The position of the nozzle opposite that side of the tunnel in 55 which there is no nozzle-section extends, therefore, in advance of the lower portions with respect to the direction in which the air flows.

With the discharge-nozzle constructed as hereinbefore described it will be observed 60 that the air-blast is discharged into the tunnel from the chamber 3 in the manner described in our prior patent, so that the said blast will enter the tunnel in a direction substantially parallel to the axis of the tunnel 65 and adjacent to the walls of said tunnel.

This mode of operation is the same as in our

prior patented construction, the effect of the air blown into the tapered chamber 3 being to cause the air to issue through the nozzle 7 at an accelerated velocity adjacent to the 70 walls of the tunnel in lines substantially parallel to the axis of the tunnel, thereby inducing a current through the tunnel, and thus clearing the same of foul air and deleterious gases, which are replaced by fresh air following 75 said induced current.

What we claim, and desire to secure by Letters Patent, is—

1. In a ventilating system for tunnels, the combination with the tunnel, of a chamber 80 formed in the wall of said tunnel, said chamber terminating in an opening adapted to discharge a blast of air into the tunnel and extending partly around the tunnel-section, the edge of one portion of said opening extending in a direction opposite to the course of the air-blast to a point in rear of the other portions thereof, with respect to the direction of the discharge of air therefrom, and means for blowing a blast of air into the chamber, substantially as described. 90

2. In a ventilating system for tunnels, the combination with the tunnel, of an air-chamber formed in the wall of said tunnel, the inner wall of which chamber is substantially in 95 line with the inner wall of the tunnel and forming with the tunnel-wall an opening adapted to discharge air therefrom, in a direction substantially parallel to the axis of the tunnel, and adjacent to the walls thereof, the edge of the air-chamber forming the discharge end of said chamber being inclined in a direction contrary to the course of the air-blast, and means for blowing a blast of air into said chamber, whereby the blast of 105 air issuing from the chamber into the tunnel will create a current through the tunnel and eddies in the current will be prevented, substantially as described. 100

3. In a ventilating system for tunnels, the combination with the tunnel, of an air-chamber formed in the wall of said tunnel, the inner wall of which chamber is substantially in line with the inner wall of the tunnel, and forming with the tunnel-wall an opening 110 adapted to discharge air therefrom in a direction substantially parallel to the axis of the tunnel and adjacent to the walls thereof, the edge of the inner wall of the chamber forming the discharge end of said chamber 115 terminating in a portion lying in a plane at right angles to the axis of the tunnel near the top portion, and extending in a plane inclined in the opposite direction to the course of the air-blast, substantially as described. 120

4. In a ventilating system for tunnels, the combination with the tunnel, of an air-chamber forming the walls thereof, said chamber terminating in a nozzle adapted to discharge air into the tunnel adjacent to the walls thereof, and substantially parallel to the axis of the tunnel, said nozzle having its discharg- 125 130 135

ing edge inclined in the opposite direction to the course of the air-blast so that the center of gravity of the air-blast discharged therefrom is substantially coincident with the center of gravity of the tunnel-section, and means for blowing air into said air-chamber, substantially as described.

5 In testimony whereof we have signed our

names to this specification in the presence of two subscribing witnesses.
